LEO RANNEY, OF NEW YORK, N. Y., AND CHARLES O. FAIRBANK, OF PETROLIA, ONTARIO, CANADA, ASSIGNEES OF ONE-HALF TO STANDARD OIL DEVELOPMENT COMPANY, A CORPORATION OF DELAWARE

METHOD OF FACILITATING FLOW FROM WELLS

Application filed July 21, 1928. Serial No. 294,569.

This invention relates to improvements in methods of facilitating flow from wells. The invention is especially applicable to the cleaning of oil wells in which deposits of 5 paraffin, calcite, or the like, have obstructed the flow from the oil-bearing formation.

Reference is to be made to the accompanying drawings, in which.

Fig. 1 is a vertical section through the lower part of a well, showing a bailer; and

Fig. 2 is a similar view illustrating a well packing.

In Fig. 1, numeral 1 indicates a well casing seated in a cap rock 2 overlying an oil sand 3. The bore of the well is extended through the oil sand and the opening 4 in the sand may be enlarged as by blasting or reaming. A bailer or agitating device 5 is suspended in the casing by a cable 6.

Fig. 2 shows a packer 7 carried by the end of a string of tubing 8. This packer is of the type which is set by the weight of the tubing and released by lifting the tubing. A tripper 9 may extend through the packing.

The tripper may be hollow if it is intended to run liquid through the tubing, or it may be solid so as to prevent any escape of gas.

The improved method will be fully understood from the following description of its use for increasing production from an oil well.

The fluid level in the well is lowered by rapid bailing or pumping to the lowest practicable point. Any tubing or other equipment in the well casing is removed and an acid is introduced into the well by means of a dump bailer or otherwise. Hydrochloric acid or nitric acid is preferred to sulfuric acid, though the latter may be used where difficulty is not encountered due to the formation of calcium sulphate. Mixtures of these acids may be used; other acids are operative but in general are too expensive.

The treating solution should be brought into contact with the entire exposed surface of the oil sand. This may be done by maintaining a solution level at the top of the oil sand, or if this is not practical, agitation may be provided to splash the solution against the sand, as subsequently described. For exam-

ple, the bailer 5 shown in Fig. 1 may be used for this purpose.

A charge of a gas-generating chemical is added to the acid. This chemical is one which evolves a large amount of heat by reaction with the acid and/or water, simultaneously liberating a gas, preferably a hydrocarbon gas, soluble in the oil. Metallic carbides are best adapted for this purpose. Calcium carbide, which yields acetylene, is preferred. 60 Aluminum carbide, which yields methane, may also be used.

In some cases we increase the heating effect by igniting the gas produced by the reaction. Any suitable ignition means may be used, 65 but it is generally most convenient to add a substance which upon contact with the charge will spontaneously ignite the gas. This substance may be a peroxide, such as sodium peroxide, or it may be an alkali metal or the like which produces heat and flame on contact with water. Sodium peroxide is especially well adapted for this purpose since it yields oxygen and thus enables the combustion to be continued independent of the air 70 normally available in the well. Additional oxygen or air may be supplied through pipes from the surface, or otherwise.

In general, soon after the reagents are placed in the well a removable packer is set 80 at approximately the top of the oil sand to confine gas formed by the reaction (see Fig. 2). It is sometimes necessary, however, to allow time for the acid to dissolve away any deposit of calcite from the walls of the well 85 before setting the packer. Also, if considerable paraffin has accumulated on the walls of the well, it may be desirable to bail out the molten paraffin and introduce fresh chemicals before setting the packer. In serious 90 cases, several applications of acid are required to remove calcite sufficiently for the entrance of gas into the pores of the sand.

The pressure generated below the packer, as described, causes the gas to penetrate outwardly into the oil sand where it is dissolved by the oil. The viscosity of the oil is considerably reduced and flow is correspondingly facilitated. The pressure also drives the acid into the sand so that it may act upon any 100

calcite or other deposits which cement the sand grains together. Paraffin, asphalt, oxidized or saponified oil, and other obstructing carbonaceous deposits, are melted by the heat of reaction. The violent agitation of the reaction mass by boiling and escape of gas exerts a washing action on the wall of the well.

When the reaction mass begins to cool, the packer is removed and the well is bailed or pumped while the fluids in it are still at a temperature above that at which paraffin congeals. Bailing should be from the bottom of the well so that all the dislodged obstructing materials are removed. Pumping is then started as soon as possible, suction being taken near the bottom of the well so as to prevent the development of back pressure by the accumulation of a fluid column. Since the acid is neutralized or almost neutralized by reaction with the added chemicals or the calcite, etc., there is no substantial corrosion of the equipment. If the primary purpose is to generate heat, the acid and gas-forming material may be used in chemically equivalent amounts. If calcite or the like is to be dissolved to increase the porosity of the sand, acid should be used in excess.

The use of a packer is generally very advantageous. However, it may sometimes be omitted, for example, during the first of a series of treatments when it is necessary to treat the well several times in the manner described for the removal of very resistant obstructions. It will be understood that the reagents may be added in any order or simultaneously.

An alternative plan contemplates treatment of the well with the reagents specified, and by the methods proposed, in sequence. In this procedure, a "string" of tubing is run into the well, supporting a wall packer at its lower end, designed to close off the space between the tubing and outer casing or wall of the well immediately above the oil sand. A bailer is provided having a diameter sufficiently small to permit of its free passage through the tubing. The fluid in the well is bailed down as far as may be practicable, and a quantity of acid of sufficient strength to attack the carbonate deposits on and within the wall rocks, is introduced. The quantity of acid used should be in excess of that which will react with calcite or other deposits. If possible, the volume of acid solution should be sufficient to nearly fill the well to the top of the oil-producing formation. If this is not feasible, a smaller quantity may be used and the bailer churned up and down in it to splash it thoroughly and repeatedly over the walls. Air pressure is applied through the tubing to force the acid to enter the pore spaces of the wall rocks. The pressure so provided will also be assisted to some extent by the pressure of carbon dioxide generated

by action of the acid on the carbonate materials.

After the acid has been forced into the wall rocks as far as the available pressure permits, the pressure is relieved at the tubing head and a charge of carbide or other heat-producing reagent is dumped into the well or lowered to the bottom with the bailer. Reaction of this material with the residual acid and water in the bottom of the well, will create heat, which melts paraffin and other solid hydrocarbons on and within the wall rocks. The bailer is withdrawn, and a swab is operated in the tubing to draw all molten paraffin and residual acid from the pore spaces of the wall rocks into the well. The fluid material is then quickly bailed out before it has had time to cool appreciably.

The following is a specific example of our method, as practiced with acid solution and gas generation operating at the same time:

To an oil well containing water, commercial concentrated hydrochloric acid and granular calcium carbide are introduced at the rate of about 50 pounds each for each 10 feet of sand depth. The acid may be dilute, as even weak acid will dissolve the mineral carbonates. Next, about 5 pounds of sodium peroxide are added and within a few minutes a packer is set at about the level of the top of the oil sand. The reaction mixture is allowed to remain in the well for about two hours and is then bailed out, after which the same process may be repeated if necessary. Pumping is begun immediately with an oil production of about five times that obtained before treating the well. The yield will ordinarily be increased three to ten times or more.

The method described is most useful in connection with the regeneration of surface oil wells, but it may be advantageously applied also to mine wells for the production of oil, and in other connections.

The preceding description is merely illustrative and various changes and alternative procedures may be adopted within the scope of the appended claims in which it is our intention to claim all novelty inherent in the invention as broadly as the prior art permits.

We claim:

1. In the chemical treatment of wells for facilitating flow therefrom, the improvement which comprises charging into the well an acid and a substance evolving heat and liberating a hydrocarbon gas upon reaction with the acid.

2. In the chemical treatment of wells for facilitating flow therefrom, the improvement which comprises charging into the well an acid and a metallic carbide.

3. In the chemical treatment of wells for facilitating flow therefrom, the improvement which comprises charging into the well hydrochloric acid and a metallic carbide.

4. In the chemical treatment of oil wells for facilitating flow therefrom, the improvement which comprises charging into the well an acid and a metallic carbide, and maintaining a pressure upon the zone in which the acid and carbide react, whereby the gas produced is forced outwardly into the oil-bearing formation.
5. Method according to claim 4 in which compressed air is introduced into the well.
6. In the chemical treatment of oil wells for facilitating flow therefrom, the improvement which comprises charging into the well hydrochloric acid and calcium carbide, obstructing the well to prevent escape of gas therefrom, whereby the gas is forced outwardly into the oil sand, and removing the reaction mass from the well before the mass has cooled.
7. Method according to claim 6, in which the acid and carbide are used in amount about 50 pounds each for each ten feet of sand thickness.
8. In the chemical treatment of oil wells for facilitating flow therefrom, the improvement which comprises charging into the well an acid and a substance evolving heat and liberating a hydrocarbon gas upon reaction with the acid, and igniting said gas.
9. Method according to claim 8, in which the gas is ignited by means of a substance spontaneously inflammable on contact with the reaction mixture.
10. Method according to claim 8, in which the gas is ignited spontaneously by a substance which yields free oxygen on contact with the reaction mixture.
11. In the chemical treatment of wells for facilitating flow therefrom, the improvement which comprises charging into the well an acid and a substance evolving heat and liberating a hydrocarbon gas upon reaction with the acid, and agitating the solution formed by the acid so as to bring the same into intimate contact with clogging deposits on the sides of the well.
12. Method according to claim 11 in which the reaction is carried on in the presence of water originally in the well or supplied thereto.
13. Method according to claim 11 in which the acid and gas are forced outwardly into the oil-bearing formation.

LEO RANNEY.

CHARLES O. FAIRBANK.
